(57) **CLAIM**

The ornamental design for a storage box, as shown and described.

DESCRIPTION

FIG. 1 is a front, top and right-side perspective view of a storage box showing my new design;

FIG. 2 is a front view thereof; with the rear view being a mirror image thereof.

FIG. 3 is a top view thereof;

FIG. 4 is a bottom view thereof; and,

FIG. 5 is a right-side view thereof; with the left-side view being a mirror image thereof.

The oblique line shading shown represents transparent surfaces.

1 Claim, 5 Drawing Sheets
